MAGAZINE LOADER

William C. Wossum, Pasadena, Calif.

Application March 20, 1943, Serial No. 479,847

5 Claims. (Cl. 86—47)

(Granted under the act of March 3, 1883, as amended April 30, 1928; 370 O. G. 757)

The invention described herein may be manufactured and used by or for the Government for governmental purposes without the payment to me of any royalty thereon.

This invention relates to a machine for loading gun magazines.

The object of the invention is to provide a machine exceedingly simple in construction by the use of which the rapid loading of the magazine will be greatly facilitated, and one whose operation requires little physical exertion, and one that will enable the proper placing of tracer bullets so their position as well as the position of others, all visible to the operator, can be noted, thus enabling the bullets to be fed to the magazine to be placed in predetermined order with error chance in arrangement reduced to a minimum, it being understood that it is customary in practice to distinguish the tracer ammunition from the other by a suitable mark.

The magazine holder in the present embodiment of the invention is designed to receive the magazine of a well known submachine gun, which magazine is of very considerable length and adapted for insertion in the gun receiver in a vertical direction, and in which the cartridges are arranged in staggered relation.

In the machine about to be described the magazine is loaded while in horizontal position.

In the drawing illustrating the invention:

Fig. 1 is a side elevation, partly broken away, showing a magazine in position to be loaded, with the plunger in the position wherein it supports a cartridge preparatory to dropping it in position to be forced into the magazine against the resistance of the spring that backs the cartridge follower in the magazine.

Fig. 2 is a plan view, with the parts in the position shown in Figure 1, with the chute removed.

Fig. 3 is a front elevation of the chute, the machine body being in section, about upon the line 3—3 of Figure 1.

Fig. 4 is a fragmentary side view, broken away in parts and showing the plunger in position to be moved forward to force a cartridge into the magazine.

The numeral 1 designates the body of the machine which may be made of any suitable material and is generally rectangular in shape. The parts mounted on the body put no considerable strain upon it in operation therefore many cheap easily obtainable materials are available for its manufacture.

One end of the body is provided with a cavity 2 or receiver for the magazine 3 to be loaded.

The magazine, for the loading of which this machine, in the illustrated embodiment of the invention is designed, is provided with a transverse lip 4 near its loading end, and consequently the floor 5 of the cavity 2 is provided with a recess 6 for the reception of the lip 4 when the magazine 3 is snugly fitted in the cavity in loading position. The side walls 7 of the cavity are contracted as indicated at 8 to form a pocket into which the cartridges *a* fall by gravity, nose down, in the loading operation.

One end of the body has an opening 9 for a plunger 10, whose forward end is provided with an arcuate recess of a curvature in agreement 15 with that of the cartridge shell. The plunger has a cross-head 11, with trunnions 12 on its ends by which it has pivotal connection with oppositely disposed links 13 and 14, the link 14 being pivotally connected at 15 with an arm 16, 20 on one side of the machine, the link 13 on the other side of the machine being similarly connected at 17 to the operating arm 18, and arms 16 and 18 are rigidly connected by a shaft 16' journaled in the body of the machine near its base.

The numeral 19 indicates an inclined open top chute which may be supported at its delivery end by a block 20 on the body 1, which is supplemented by two oppositely disposed standards 21, whose upper and lower ends are attached to the chute and body respectively.

Preferably there is a curved guard or apron 22, over the curved lower end of the chute, the curved portions of the chute and apron being 35 so spaced with relation to each other as to preclude the possibility of the cartridges bending at the turn.

The rearward movement of the plunger may be limited by a pin 23 extending laterally from the 40 side of the machine, for engagement with the operating lever, and its forward movement will be limited by the crosshead 11. The range of movement of the plunger in its reciprocation is such as to take its feeding end entirely out of 45 the pocket 8, when the plunger is in its extreme rearward position, and extends into the pocket when in forward position for a distance allowed by the crosshead 11.

The magazine 3 of the type which the machine 50 is designed to load has two oppositely disposed slightly inturned lips *b*, inturned flanges *c*, and a spring backed follower *d*, the follower being provided at one side with a member *e*, to shunt the cartridge off to one side of the magazine, the 55 first as well as the succeeding ones, so as to

arrange them in staggered relation in the magazine.

In operation of the machine, say putting in the first cartridge, the plunger pushes the cartridge straight out of the pocket 8, but when the cartridge engages the deflecting member e, it will be deflected to one side of the magazine, and when the next cartridge is fed in, it will engage, not the deflecting member, but the preceding cartridge, which will deflect it to the opposite side of the magazine, where under the influence of the spring-backed follower, it will be caught by the magazine lip when the plunger recedes. As the plunger comes forward in the act of feeding a cartridge, the cartridge next to be fed, rides on the top of the plunger, in vertical position as shown in Fig. 1, and in position to drop in the pocket 8 in front of the plunger when it reaches the position shown in Fig. 4.

I claim:

1. In a machine for loading cartridges into a gun magazine, in combination, a body having therein a cavity for the reception and support of a magazine and adapted to receive the cartridges in vertical position with its open end toward the cartridge supply and an open end cartridge receiving pocket opposite the loading end of the magazine narrower than the cavity and adapted to support the cartridges in vertical position in the pocket, a reciprocable plunger movable into and out of said pocket, and means for reciprocating the plunger to feed a cartridge in vertical position from the pocket to the magazine.

2. In a machine for loading cartridges into a gun magazine, in combination, a body having a cavity therein for the reception of a magazine with its loading end toward the cartridge supply, an open end cartridge receiving pocket opposite the open end of the magazine narrower than the cavity and adapted to support the cartridges in vertical position in the pocket, a plunger movable into and out of said pocket, an inclined chute supported above the body and having a curved delivery end opening above the pocket where-through a cartridge is delivered into the pocket in vertical position to be fed into the magazine in such position, the position of the plunger being such in relation to a succeeding cartridge as to support said cartridge in position to fall into said pocket while feeding the preceding one, and means for actuating the plunger to feed the cartridges.

3. In a machine for loading cartridges into a gun magazine, in combination, a body having a cavity therein for receiving a magazine with its loading end toward the cartridge supply, an open end cartridge receiving pocket opposite the open end of the magazine narrower than the cavity and adapted to support the cartridges in vertical position in the pocket, a chute in which the cartridges are visibly supported, the delivery end of the chute being positioned to deliver the cartridges into said pocket, a plunger movable into and out of said pocket to feed the cartridges into the magazine, and means for reciprocating the plunger.
4. In a machine for loading cartridges into a gun magazine, in combination, a body having a cavity therein for the reception of a magazine, a cartridge receiving pocket opposite the open end of the magazine to receive the cartridges as they are fed, means for feeding the cartridges to the pocket in vertical position, a plunger supported in the body for feeding cartridges from the pocket into the magazine, said plunger having a cross-head outside the body, two links pivotally connected to the cross-head, one on one side of the machine and one on the other, a transverse shaft journaled in the body and having a rigid arm on one end to which one of said links is pivoted, and an operating lever rigidly attached to the opposite end of the shaft, said lever being pivotally connected with the other of said links.
5. In a machine for loading cartridges into a gun magazine, in combination, a body having an elongated cavity therein for the reception of a magazine with the loading end toward the cartridge supply, an open end cartridge receiving pocket opposite the open end of the magazine and adapted to receive the cartridges in vertical position, means for feeding the cartridges to the pocket in vertical position, said pocket being of a width substantially commensurate with the diameter of the cartridge so as to support the cartridge in vertical position, a plunger for feeding the cartridges into the magazine movable into and out of said pocket, said plunger extending normally far enough into said pocket to support a cartridge in position to fall into the pocket while feeding the preceding one into the magazine, and means for actuating the plunger.

WILLIAM C. WOSSUM.
